UNITED STATES PATENT OFFICE.

ALFRED T. CHANCE, OF BERLIN, MARYLAND.

CURTAIN-HOLDER.

No. 839,729.

Specification of Letters Patent.

Patented Dec. 25, 1906.

Application filed June 7, 1906. Serial No. 320,587.

To all whom it may concern:

Be it known that I, ALFRED T. CHANCE, a citizen of the United States, residing at Berlin, in the county of Worcester and State of Maryland, have invented certain new and useful Improvements in Curtain-Holders, of which the following is a specification.

This invention relates to curtain-holders for either windows or doors.

10 The object of this invention is to provide a curtain-holder adapted to hold the lower part of a window or door curtain back against the window or door frame, as the case may be.

15 Another object of this invention is to provide a curtain-holder of the character above described and to make the same adjustable, so as to spread the curtains apart at different degrees.

20 A further object is to provide a curtain-holder such as described and to construct the same in an exceedingly cheap and simple manner, one which may be easily and quickly applied, and will efficiently perform 25 all of its intended functions.

With these ends in view and such others as may appear my invention consists in the particular construction of the various parts and in the novel manner of combination and 30 arrangement of said parts, all of which will be hereinafter more fully described, and specifically pointed out in the appended claims.

In the drawings forming a part of this 35 specification, Figure 1 is a front view of a window and its frame provided with my invention. Fig. 2 is an enlarged detail view of the socket or retaining plate, and Fig. 3 is an enlarged detail view of the holder or hook.

40 Referring by numerals to the drawings, 1 represents a plate having countersunk screw-holes 2, by which it may be secured to a window or door frame, as the case may be. This plate is provided upon its face with a projecting semicircular portion 3, through the center of which passes a perpendicular aperture 4, and it is further provided upon its periphery with a series of recesses 5, the object 45 of which will hereinafter appear. The cur-

tain-holders proper consist of right and left 50 hand hooks 6. However, the description of one is applicable to the other, the only difference being in the direction of the bend of the hook portion. The shank 7 of the hook is formed with a downwardly-projecting pin 8, 55 adapted to engage the aperture 4 and sustain the hook in a horizontal position. This shank portion is further provided with a lip 9, which projects downwardly parallel to the pin and has a bearing against the semicircular portion of the plate. In the angle formed by the shank 7 and the lip 9 is a lug 10, adapted to engage any one of the notches or recesses 5, so as to lock the hook in any desired position, thus allowing for the adjustment of the same in order to part the curtains at various distances or degrees. 65

I deem the foregoing explanation sufficiently plain that the invention will be readily understood by all conversant in such 70 matters, the extreme simplicity rendering an elaborate description unnecessary.

Having thus described the various features of my invention, what I claim as new, and desire to secure by Letters Patent, is— 75

1. A curtain-holder comprising a semicircular support having an aperture and a series of recesses therein, a pin engaging said aperture, a horizontal hook supported by the pin, a lug carried by the hook adapted to engage the recesses, substantially as specified. 80

2. In a curtain-holder a semicircular support, means for securing the support in position, a perpendicular aperture in the support, a series of recesses in the periphery of the support, a pin engaging the aperture, a horizontal hook supported by the pin, a lip formed upon the shank of the hook adapted to bear against the semicircular portion of the support, a lug formed in the angle made by the shank and lip, said lug adapted to engage any one of the recesses, substantially as specified. 85 90

ALFRED T. CHANCE.
